UNITED STATES PATENT OFFICE.

FRITZ ARLEDTER, OF PERLEN, SWITZERLAND.

APPARATUS FOR MAKING SOAP.

SPECIFICATION forming part of Letters Patent No. 605,988, dated June 21, 1898.

Application filed September 1, 1897. Serial No. 650,268. (No model.)

To all whom it may concern:

Be it known that I, FRITZ ARLEDTER, engineer, a citizen of Switzerland, and a resident of Perlen, near Lucerne, Switzerland, 5 have invented certain new and useful Improvements in Apparatus for Making Soap, of which the following is a specification.

My invention relates to an apparatus for producing resinous soap in a more expeditious, effective, and on the whole more rational manner than hitherto known.

By the operation of my machine the lather that ascends in the resin-boiler is continuously exposed to the mechanical motion of a stirring apparatus fitted with cutting planes or knives, and simultaneously the particles of resin ascending along with the lather are being melted by a number of slotted hot metal plates. By this means an effectual partition 15 of the resin into the smallest particles is obtained, the result being resinous soap with greatly-liberated resin. At the same time the expulsion of the gases generated in boiling makes the boiling process much more 20 thorough than hitherto and also considerably shorter.

In the drawings, Figure 1 is a side view of the boiling apparatus. Figs. 2, 3, 4, and 5 are detail views of the same.

30 The resinous soap is made in the usual manner in a boiler *a*, heated by indirect steam through the steam-jacket *b*.

c is a bottom-stirrer forming the nethermost part of a shaft *d*, which during the working 35 of the bottom-stirrer is at *e* coupled to another shaft *f*. Around this shaft rotates a third shaft or sleeve *g*. The shafts *f* and *g* are by means of some transmission-gear made to rotate in opposite directions to each other.

40 In the drawings this is shown as attained by means of the two bevel-wheels *h* and *i*, respectively fastened to the upper ends of the shafts *f* and *g*, being made to rotate in opposite directions to each other by a third bevel-wheel *k*, inserted in the gearing and moved 45 from the motor by the belting *l*.

Around the shaft *g* is a sleeve *m*, sliding up and down, yet so that it always follows the rotating motion of the shaft *g*. The sleeve 50 *m* is by a connecting-rod *n* connected with another sleeve *o*, which in the same manner

is sliding up and down on its shaft *f* and rotating with this. Figs. 2 and 3 are a side view and plan view showing how the sleeve *m* may be connected with its shaft *g*. This latter is 55 shown in square section and passes through the corresponding sleeve *m*, which is square inside. Springs *p* keep, through friction, the sleeve *m* in its position, and by means of the pivoted lever *r*, looselygeared round the sleeve 60 through a loose ring *q*, the sleeve *m* may be adjusted up and down, thereby carrying the lower sleeve *o*, that may slide on the shaft *f* by means of stop and notch. The rod *n*, connecting the sleeves, may at the ends be fastened to a loose ring *s* and *t*, respectively surrounding the sleeves *m* and *o*.

Curved arms *u u* extend from the sleeves *m* and *o*, ending nethermost in the same height, and carrying here plow-shaped irons 70 or knives *v v* and *w w*. Fig. 4 is a detail plan view of one of these knives fastened to its arm *u*, and Fig. 5 is a plan view of the whole arrangement of all the knives, (here four,) turning, of course, their edges in the direction 75 of the motion. This direction is, as will be understood from what has been said above, opposite for each pair, as indicated by the arrows in Fig. 5.

x x x are fixed metal plates fitted in the 80 most suitable way to the boiler *a* and preferably adjustable up and down. The plates are fitted with longitudinal slits *y*, as shown in Fig. 1.

In my apparatus, as described above, a 85 rapid and intense partition of the millions of gas-bubbles will be effected by means of the fixed slotted plates *x*, in combination with the very effective opposite motion of the knives *v w*. In this way the usual ascent of the 90 mass during the boiling will be considerably reduced, and as a result the temperature may, through admission of steam, be raised, whereby the process is accelerated, while at the same time a thorough separation of the saponified and non-saponified resin particles is 95 effected. The resin particles ascending from below strike in circular motion constantly against the hot metal plates *x*, where they melt, and by means of the rotating motion of the knives *v w* they are continually carried 100 farther through the slits *y* and thoroughly

mixed after having been separated into the smallest particles. In this way resinous soap with greatly-liberated resin is obtained.

Having now particularly described and ascertained the nature of my said invention and in what manner the same is to be performed, I declare that what I claim is—

In combination, in an apparatus for making soap the boiler, the slitted plates α extending vertically therein, the two sets of agitators movable in the boiler in opposite directions, the shafts carrying the said agitators, one shaft passing through the other, means

for rotating the shafts and means for raising and lowering the agitators consisting of the sleeves about the shafts and connected together with means for raising and lowering the said sleeves, substantially as described.

In testimony that I claim the foregoing as my invention I have signed my name, in presence of two witnesses, this 2d day of August, 1897.

FRITZ ARLEDTER.
